UNITED STATES PATENT OFFICE

ANTHONY DICICCO, OF PROVIDENCE, RHODE ISLAND

COMBINED ENVELOPE AND CARD

Application filed April 16, 1931. Serial No. 530,705.

This invention relates to an improvement in combined envelopes and cards.

The present invention has for its primary object to provide a novel and improved mailing article combining the individual features of a pictorial postcard with those of an ordinary sealed envelope. An article so provided meets the desires of a person who wishes to mail a letter and at the same time accompanying it with a pictorial postcard, and the device presents an heretofore unpracticed and unknown psychological and commercial appeal to tourists and the like.

The object of the invention is to provide a combined envelope and picture post-card as a unitary structure, which may be sold as one and transmitted through the mails in the same manner and for the postage of a letter, while yet transmitting the pictorial face of the card as well as a letter which may be enclosed within the envelope.

It is often desirable to send through the mails both a picture postal card and a letter, and by combining the two and selling them as a unitary structure, both the envelope and the card may be obtained at once, which makes it unnecessary to purchase them separately and to pay separate postages for both the card and the envelope.

The back of the postal card is pasted or otherwise secured to the front of a complete envelope, in order to leave the pictorial front of the postal card outermost and also leaving the envelope flap exposed, for the insertion of a letter or other matter into the envelope for transmission through the mails, and to permit the sealing of the envelope. The flap of the envelope when sealed may receive the name and address of the addressee.

In the accompanying drawing:

Fig. 1 is a perspective view from the front side of the combined envelope and card;

Fig. 2 is a back view of the envelope side with the flap closed; and

Fig. 3 is a plan view of the blank for the envelope.

In the form illustrated in Figs. 1 and 2, the pictorial postal card is designated generally by the numeral 1 and has its back side attached to the face or front side of an en-

velope 2, preferably by a suitable adhesive, such as an ordinary glue or the like, although any other suitable means may be employed which will securely and permanently attach the card and envelope to each other.

The adhesive is preferably arranged over the whole face of the envelope and the card is pressed thereagainst to securely fasten the two together, and in this way all edges of the card are secured, which leaves none of the edges separated, by which there is likely to be any separation of the card from the envelope in transmitting the same through the mails.

The flap 3 at the upper edge of the envelope is made to extend over a substantial portion of the back of the envelope and, as shown in Fig. 2, it extends over approximately the entire rear face. This flap 3 has a space 4 thereon to receive the name and address of the addressee, and the stamp may be placed in the upper right hand corner, as shown at 5.

The blank from which the envelope is formed is shown in Fig. 3, where the main portion is designated by the numeral 6 and has fold-lines 7 between the said main portion and end flaps 8. The flap 3 is also separated from the main portion 6 by a fold-line 9. A bottom flap 10 may be folded over the main portion 6 along a line 11, and this bottom flap 10 has a V-shaped notch 12 in the edge thereof to cooperate with the edges of the end flaps 8.

Portions 13 along the outer edges of the bottom flap 10 may have adhesive applied thereto to secure the same over the end flaps 8, and the flap 3 also has an adhesive portion 14 along the edge thereof to seal the envelope.

In forming the envelope, the blank is folded in the usual way first by turning the end folds 8 inward and securing them in place by the glued edges 13 of the bottom flap 10, which completes the formation of the envelope, and it is then ready to receive the picture postal card 1, which has its back face adhesively secured to the front of the envelope 2 as above described.

This provides for a unitary article com-

prising both an envelope and a picture postal card which may be sold together and transmitted through the mails at the same time for the postage of only one, and it also **5** simplifies the handling of the mail by reducing the number of pieces thereof, while yet transmitting both the picture postal card and a letter in the envelope.

I claim:

- 10** 1. A combined envelope and postal card comprising a relatively stiff cardboard front having a pictorial front face, a complete envelope having a front face extending approximately co-extensive with and adhesively secured to the back face of the card approximately throughout the entire area thereof, and a closure flap carried by the top edge of the envelope and extending approximately over the area of the back of the envelope, and **15**
20 said flap providing conventional stamp and address spaces.
- 25** 2. A combined envelope and postal card comprising a relatively stiff cardboard front having a pictorial front face, a complete envelope having a front face extending approximately co-extensive with and adhesively secured to the back face of the card approximately throughout the entire area thereof, and a closure flap carried by the top **30** edge of the envelope, and said flap providing conventional stamp and address space.

In testimony whereof I affix my signature.
ANTHONY DICICCO.
